UNITED STATES PATENT OFFICE.

JOHN KERTES, OF PITTSBURGH, PENNSYLVANIA.

TILE, QUARRY, OR BRICK.

1,058,674.

Specification of Letters Patent.

Patented Apr. 8, 1913.

Application filed September 16, 1911. Serial No. 649,773.

To all whom it may concern:

Be it known that I, JOHN KERTES, residing at Pittsburgh, Pennsylvania, in the United States of America, have invented a certain new and useful Form of Tile, Quarry, or Brick; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to an improvement in tile, quarry or building brick.

The object of the invention is to provide improved tile, quarry or brick which are self tying or binding when laid in cement or mortar, which are not liable to settle or change their position after being laid, and which are provided with means for regularly spacing the same apart.

20 The invention comprises the construction and arrangement of parts hereinafter described and claimed.

In the drawings Figure 1 represents a perspective view of a building brick constructed according to my invention; Fig. 2 30 represents a perspective elevation of a section of wall laid with such brick, the mortar being omitted; Fig. 3 is a perspective view of a quarry or tile constructed according to my invention; Fig. 4 is an elevation of the 35 same; Fig. 5 is a plan view of the underside of such a quarry or tile; Fig. 6 is a plan view of a number of the quarries or tiles shown in Fig. 3 as the same appear when laid in position; and Fig. 7 is a similar view 40 showing a modified form of tile or quarry.

The brick 1 shown in Fig. 1, is of the usual form of building brick and preferably is made of standard dimensions, and is provided with top and bottom faces 2, opposite 45 side faces 3 and side or end faces 4. The brick shown is provided with suitable means for spacing it above other brick upon which it is laid and from adjacent brick in the same horizontal row. As shown, the brick 1 is provided with one or more ribs or projections 5 upon one of its flat top or bottom faces 2, four being shown in the embodiment illus-

trated. The ribs 5 are triangular in cross section and merge into a comparatively sharp ridge or edge 6 extending transversely of the direction of the length of the brick. These ribs or projections 5 are formed in pairs as shown, two thereof being in line with each other, and if desired they may be formed continuous, or as one. One side or end face 4 of the brick is provided with similar ribs or projections 7 which extend across the end face and from the top to the bottom of the brick. Preferably, these ribs or projections 7 are spaced different distances from the joining edges 8 between the end and other side faces of the brick. In other words, one of the ribs is farther from its nearest edge than the other, for a purpose to be described.

70 The brick shown in Fig. 1 is used in the manner shown in Fig. 2. A bottom or foundation row 9 of the brick having been laid, a layer of mortar or cement (not shown) is spread upon the upper face of the row 9. 75 This layer is preferably made somewhat thicker than the depth of the ribs or projections 5. A row 11 of bricks 1 is then laid upon the row 9. These bricks are laid successively end to end and each in turn is 80 pressed downwardly into the layer of mortar in such manner that the edges 6 of the ribs 5 cut their way through the mortar and enable the brick to be forced into direct and firm contact with the adjacent brick of the 85 lower row 9.

As shown in Fig. 1, one end face 4 of each of the brick is flat and not provided with projections or ribs. The brick are laid successively with the end ribs 7 of one brick 90 resting against the flat end face 5 of the next brick. By reason of the construction described, successive rows of brick laid upon each other are separated by regular spaces or distances determined by the depth of the 95 ribs or projections 5 of the brick used. Also, successive bricks in the same row are spaced or separated from each other by the depth of the ribs or projections 7. Moreover, with a wall laid of such brick, the brick having 100 direct contact or bearing of row upon row precludes the possibility of settling of the wall after the same has been laid before drying or hardening of the cement or mortar.

Furthermore, the distance between rows and between bricks is exactly regulated by the brick themselves and less skilled labor is, therefore, required to lay them.

- 5 By reason of the fact that the ribs 7 are formed only upon one end face of the brick, and are spaced different distances from the edges 8, it is possible to build a wall finished at both ends with a single style of brick.
- 10 For example, if the section of wall shown in Fig. 2 is built from left to right with the bricks arranged to break joints, the last brick 12 at the right may be reversed in position, when the projections 7 on the brick 12 and 13 will overlap each other by reason of their unequal spacing, as stated.

Fig. 3 illustrates a tile or quarry constructed according to my invention. This is formed as a comparatively thin rectangular slab of material formed with projections or ribs 14 upon two of its narrow side or edge faces 15. Preferably, the bottom face of the tile 14 is formed with a number of comparatively shallow projections 17 to enable the 20 tiles or quarries to be stacked upon each other during burning thereof, and the hot air or gases to penetrate through the stack and complete the burning in less time and more uniformly. The tiles or quarries 25 shown in Fig. 3 may be of any dimension, either in length or breadth, and are laid in a wall or floor as shown in Fig. 6. The ribs or projections 14 may be formed either with sharp edges or with flat end faces 19, as 30 shown, to provide firm bearing between adjacent tiles or quarries. Preferably, a plurality of the ribs or projections are formed on a single side face to prevent wabbling of the tile when held in contact with each other.

35 40 If preferred, my invention may be applied to other forms or shapes of tiles or quarries than that shown in Figs. 2 and 3. Fig. 7 illustrates the application of my invention to hexagonal tiles or quarries 20. These are 45 formed with one or more ribs or projections 21 upon one of their side faces 22 and, upon each of the side faces 23 adjacent to the face 22, with a single rib or projection 21. The tiles or quarries so formed are laid as shown 50 in Fig. 7, with the ribs or projections 21 spacing adjacent tiles or quarries from each other by definite distances regulated by the length or depth of the ribs of the tiles or quarries used. By providing a plurality of 55 ribs 21 upon one face of each of the hexagonal tiles shown, all wabbling or displacement of the tiles or quarries in their bed of mortar or cement is prevented after the laying of the tiles therein. This result follows 60 from the arrangement shown in Fig. 7 in which any particular tile, as for example, that lettered A, is spaced from the next tile B, in one direction, by the ribs 21 upon the tile A, and from the next adjacent tile C, in 65 the opposite direction, by the ribs 21 upon

tile C. The ribs 21 upon the tiles or quarries 20 may obviously be either of the form of the ribs 5 shown in Fig. 1 or of the ribs or projections 14 illustrated in Fig. 3.

70 Walls or floors constructed with the improved bricks, tiles or quarries illustrated, are much stronger than those formed with ordinary bricks, tiles or quarries since slipping of one upon another is practically impossible. In the wall shown in Fig. 2, the 75 ribs 7 prevent horizontal movement of the bricks sidewise from the wall while the ribs 5 prevent endwise movement of one row upon the next. The brick is, therefore, self tying or binding and if properly pressed down into the cement or mortar until the ribs or projections reach full bearing upon adjacent brick, does not easily become displaced from position. It will further be observed that the ribs or projections 5 are 80 spaced inwardly from the side faces of the brick. Therefore, when the brick are laid in a wall and are bedded in cement or mortar, the latter covers up the ends of the ribs 5 and hides them from view on the outside of 85 the wall. A wall so constructed, therefore, 90 presents a finished appearance.

The tiles or quarries shown in Figs. 6 and 7 may be laid in the manner indicated, either 95 in a floor or wall. If laid in the form of a wall, each tile or quarry is exactly spaced from every other tile or quarry and cannot wabble or assume an improper position in the wall. During laying thereof, it will also be observed, as indicated in Fig. 3, that the 100 projections 14 are spaced from the flat faces 24 of the tile or quarry. When these tiles or quarries are laid in position, the ribs or projections 14 and 21 are, therefore, hidden or concealed by the cement or mortar holding 105 them in place. The bricks having these ribs or projections do not, therefore, detract from the appearance of the finished wall or floor, as will be observed. Furthermore, the ribs or projections 14 and 21 make the tiles or 110 quarries self tying or binding in the same manner as the form of brick illustrated in Fig. 1.

What I claim is:

1. A brick provided with top, bottom, end 115 and side faces, said bottom face being provided with a plurality of ribs extending in a direction from side to side of the brick, one of said end faces being provided with a plurality of ribs extending from top to bottom 120 of the brick, said end ribs being spaced at different distances from the side faces of said brick.

2. A wall composed wholly of similar 125 bricks, each brick having top, bottom, end, and side faces, the bottom face being provided with a plurality of ribs extending in a direction from side to side of the brick, one of said end faces being provided with a plurality of ribs extending from top to bottom 130

of the brick, said end ribs being spaced different distances from the side faces of said brick, said bricks being placed end to end in said wall with the end ribs spacing adjacent 5 bricks apart endwise, and the end bricks in the wall being reversed in position with their end ribs overlapping the ribs on the ends of the next adjacent bricks.

In testimony whereof I affix my signature in presence of two witnesses. 10
Pittsburgh, Pa. U. S. A. 4 September 1911.

JOHN KERTEs.
